UNITED STATES PATENT OFFICE.

JOHN ROWLAND BROWN, OF MANSFIELD, OHIO, ASSIGNOR TO THE OHIO BEASS COMPANY, OF MANSFIELD, OHIO, A CORPORATION OF NEW JERSEY.

RAIL-BOND.

1,336,940.

Specification of Letters Patent.

Patented Apr. 13, 1920.

Application filed November 2, 1917. Serial No. 199,959.

To all whom it may concern:

Be it known that I, JOHN ROWLAND BROWN, a citizen of the United States, residing at Mansfield, in the county of Richland and State of Ohio, have invented certain new and useful Improvements in Rail-Bonds, of which the following is a specification.

This invention relates to such devices known as rail bonds used for electrically bridging the adjacent ends of rails used as a return circuit for the operation of electric cars.

The primary object of this invention is to produce a rail bond adapted to be secured to the surface of rails by means of an attaching metal and the application of heat, and which is simple and durable in construction, effective in operation, and which will give high electrical efficiency.

Another object of this invention is to produce a rail bond adapted to be welded to the surface of rails and provided with a plurality of surfaces, adapted to receive the attaching metal, disposed in angular relation with respect to each other.

A further object of the invention is to produce a bond that can be applied to the surface of rails in various positions and having terminal members of a higher melting point than the body portion thereof.

To the attainment of these ends and the accomplishment of other new and useful objects, as will appear, the invention consists in the features of novelty in the construction, combination and arrangement of the several parts hereinafter more fully described and claimed and shown in the accompanying drawings illustrating the embodiment of the invention and in which:

Figure 1 is a side, elevational view of a rail joint of the type ordinarily found in use and showing my bond applied thereto in two positions, the bond being shown in solid lines as usually applied to this type of joint, and in dotted lines in the position in which it is applied to a different type of rail joint in which the constructional arrangement and relation of the various parts will not permit of the former application thereof.

Fig. 2 is a transverse sectional view of Fig. 1.

Fig. 3 is a side view of a bond embodying the principles of my invention.

55

Fig. 4 is a top view of a portion of the bond.

Fig. 5 is an end view of the bond.

Figs. 6 and 7 are views of a modification of the invention herein disclosed.

60

Fig. 8 is a top view of another modification of the invention.

Figs. 9 and 10 are views of opposite sides of the construction shown in Fig. 8.

Fig. 11 is an end view of Fig. 10.

65

Referring to the drawings in which similar reference characters indicate like parts in the different views, 1—1 designate portions of two adjacent rails of an electric railway shown as electrically connected by a bond embodying the principle of my invention and consisting of a flexible body member 2, usually composed of a plurality of strands of copper, having securely attached to each end thereof a terminal member 3, the bond being attached to the rails by means of an attaching metal 4, and the application of heat.

75

The terminal member 3 of the present invention is composed of ferrous metal which is particularly adapted to this type of bond and is preferably formed as shown in Figs. 3 and 4, the sides 5—5 thereof projecting a greater distance from the surface of the body member than the remaining side, the upper end surfaces of which provide a shelf for receiving the attaching metal 4. The terminal member 3 partially encircles the body member 2, leaving the end surface 6, which projects a slight distance beyond the end of the terminal members 3, and a portion of the side surface, indicated at 7, exposed for receiving the attaching metal 4, and is secured to the body member by compression and maintained in locking engagement therewith by means of the projections 8, which are adapted to engage the body member in gripping relation. The projections 8 are further adapted to contact with the surface of the rail, thereby providing a space or vent between the adjacent surfaces of the rail and the body member in order to facilitate the operation of welding when the bond is applied to the rails in the position as shown in the upper portions of Figs. 1 and 2, the body member thereof resting in a ver-

105

tical position, in which case the attaching metal 4 is welded to the terminal member 3 and the end surface of the body member 2, and in overlapping relation therewith, 5 and to the side surface of the rail, thus effecting a homogeneous connection of the parts of great mechanical strength, and of high electrical efficiency.

The exposed side portion 7 of the body 10 member is adapted to receive the attaching metal when the bond is applied to the rails as shown in dotted lines, or the body member thereof resting in a horizontal position. While I have shown the bond attached to 15 the base of the rails in this position, it will be obvious that it is equally adaptable to be applied to the ball of the rails in a similar position.

Figs. 6 and 7 show a modified form of my 20 invention disclosed in Figs. 3 and 4 in that the terminal member has the opposite side compressed into converging contact with the body of the bond thus more tightly compressing and compacting the members of 25 the bond body together.

Figs. 8, 9, 10 and 11 are views of another 30 form of the invention which consists in forming the terminal member 3 up out of a comparatively thin piece of sheet metal. The terminal comprises the shelf 10, produced by folding the metal upon itself, the bond being squeezed to such a degree as to 35 press the parts of the fold tightly together, as indicated at 11, Fig. 8, thus eliminating all space between the upper and lower parts of the fold. Flanges 12 and 13, are formed out of the respective parts of the fold and are adapted to contact with the surface of the body member 2, the flange 13 being 40 provided with projecting ends 14 which engage the exposed side surface 7 of the body member and are adapted to maintain the terminal member 3 in locking engagement with the body member 2 and which provide

also for spacing the body member from the 45 rail in order to facilitate the operation of welding as before stated.

Having fully described my invention and shown several forms embodying the same, I do not wish to be limited to the details of the 50 construction shown, since these can be obviously changed without departing from the spirit and scope of the invention.

I claim:

1. A rail bond comprising a bond body 55 composed of copper, and a terminal member composed of ferrous metal, the terminal partially encircling the bond body and comprising a shelf having a flange provided with inwardly extending projections adapted to engage the unencircled portion of the bond body for the purpose of securing the terminal and body together, the shelf being formed by folding the metal upon itself in such a manner as to eliminate all space between the parts of the fold. 60

2. A rail bond comprising a bond body and a terminal member, one face of the body being exposed, the terminal member provided with a projecting portion to receive 70 and support an attaching metal and having a transverse slot in one face to receive the bond body and having means to engage the exposed face of the bond body to secure the body and terminal together. 75

3. A rail bond comprising a bond body and a terminal member, one face of the bond body being exposed, the terminal member provided with a projecting portion intermediate its ends to receive and support an 80 attaching metal and having a transverse slot in one face to receive the bond body and having means to engage the exposed face of the body to secure the body and terminal together. 85

In testimony whereof I affix my signature.

JOHN ROWLAND BROWN.
